STAMPING DEVICE FOR PACKERS

James W. Leary, Bloomfield, N. J., assignor to
American Machine & Foundry Company, a
corporation of New Jersey

Application April 12, 1934, Serial No. 720,340

8 Claims. (Cl. 216—57)

This invention relates to improvements in packaging machines generally, and more particularly to the stamping device of machines for packaging pulverulent materials, of the type disclosed in Patent No. 1,058,579, granted April 8, 1913 on the application of G. W. Gwinn.

The main object of the invention is to provide a stamping device which will operate more efficiently by reason of its novel mode of operation. 10 In prior stamping devices of the type disclosed in the above mentioned patent the top flap of the pouch enclosing the material being packaged is held down adjacent its base by a flap-presser while the stamp is laid across the top of the package beyond the edge of the flap-presser. With the present device the stamp is drawn over the top of the package in overlying relation to the flap-presser and held down on the top of the package while the package is raised between stationary 15 brushes, as in the prior devices, which wipe the ends of the stamp down over the sides of the package. In the present device, however, the stamp, after the package has been subsequently tilted forward to withdraw the flap-presser from under the stamp, covers a greater area of the top flap and thus holds the latter more firmly and securely.

A further object of the invention is to simplify the construction of the stamp-presser. The novel 20 mode of operation of the device makes it possible to dispense with the cam controlled mechanism common in prior stamping devices for actuating the stamp-presser.

With these and other objects not specifically 25 mentioned in view, the invention consists in certain constructions and combinations hereinafter fully described and then specifically set forth in the claims hereunto appended.

The motion for operating the stamping device 30 is derived from the same lever and cam system used for actuating the stamping device of the original machine, as disclosed in the patent above mentioned, and in the accompanying drawing the subject of this invention has been shown as incorporated in the packaging machine above referred to. Where the same or similar parts to those in the original machine are used, they have been given the same reference numbers.

In the accompanying drawing: 35 Fig. 1 is an elevation (partly broken) showing the features of this invention;

Fig. 2 is a sectional side view taken through the center of Fig. 1;

Fig. 3 is a sectional plan view taken on line 3—3 40 of Fig. 1;

Fig. 4 is a sectional plan view taken on line 4—4 of Fig. 1; and

Fig. 5 is a plan view of top of Fig. 1.

In carrying the invention into effect there is provided means for lifting a package vertically in upright position, a flap-presser bearing down on the top flap of the package while it is being lifted, mechanism for moving a stamp across the top of the package in overlying relation to the flap-presser, a vertically movable stamp-presser for 10 pressing the stamp down against the top of the package while the latter is being lifted, members for wiping the ends of the stamp down over the sides of the package as the latter is being lifted, and stationary guides arranged to engage the 15 back of the package as it is being lifted, the upper ends of the guides being inclined across the path of the package to tilt it and thus withdraw the flap-presser from under said stamp and withdraw the top of the package from contact with 20 said stamp-presser. In the best constructions contemplated, there is also provided stationary rollers arranged to engage the top of the package at the end of its upward movement, a pusher for 25 ejecting the stamped package sidewise from said means, and a curved guide strip for tilting the package back into upright position as it is being ejected. The package lifting means in the best 30 constructions may include a vertically reciprocable pusher plate; the flap-presser includes a vertically movable slide and a resilient flap-presser plate mounted on the slide; and the stamp-presser includes a slide, stamp-presser 35 rollers on said slide, and a stop for supporting said slide with its rollers in position to engage the stamp on the top of the package being lifted. These various means and parts may be widely 40 varied in construction within the scope of the claims for the particular device selected to illustrate the invention is but one of many possible concrete embodiments of the same. The invention, therefore, is not to be restricted to the specific construction shown and described.

As the turret 100 turns periodically, Figs. 1 and 45 2, it brings the successive pockets 99 thereof, together with the packages therein, into registry with pusher 193, the top flap of each pouch B successively riding under the resilient flap-presser plate 301 on flap-presser slide 302. Pusher plate 193 on rod 192, which is periodically reciprocated by mechanism shown in the above mentioned patent, starts the package through pocket 99, and since the motion of the flap-presser slide 302 is slightly delayed relative to the motion of the pusher, it causes presser plate 301 to bear down 50 55

on the top flap of pouch B and thus hold the package firmly on the pusher. As the package proceeds up through pocket 99 and into the stationary guide 303 it picks up the stamp or label 5 S, which, in the meantime, has been drawn from the stamp magazine 215 over the paste roller of a stamp pasting mechanism (not shown) by gripper jaws 239 and 240, and deposited across the top of guide 303 in overlying relation to the presser plate 301. The gripper actuating mechanism and stamp pasting mechanism are clearly shown in the above mentioned patent to which reference may be had for a complete disclosure of the same. After the package has contacted with stamp S 10 it encounters stamp-presser rollers 304 on stamp-presser slide 305 which slides freely on guide bars 308 and by its weight causes rollers 304 to bear down on the stamp S, holding it securely to the top of the package until the paste on its under 15 face has had time to set and unite it to the package. The slide 305 normally rests on a stop set in one of the bars 308, until it is raised therefrom by an ascending package.

As the package, with the stamp across its top, 20 continues its upward motion, the overhanging ends of the stamp S encounter brushes 167 which sweep the ends of the stamp down against the narrow sides of the package. The brushes 167 are adjustably mounted in order to provide a suitable pressure to properly brush the stamp so as to secure it to the package.

The operation of attaching the stamp to the package is now completed, and as the package continues its movement up to the delivery level, 25 the upper back corner of the package encounters the inclined upper end of the guides 306a and 306b which compel the package to assume a gradually increasing tilt forward and, in so doing, withdraws the flap-presser plate 301 from under the stamp and withdraws the top of the package from under stamp-presser rollers 304.

As the package reaches the delivery level, at the limit of the stroke of pusher 193, the top of the package bears against stationary rollers 307, and pusher 195 proceeds to eject it from pusher 193 onto the delivery table 164. While being pushed onto the delivery table the package travels under the row of rollers 307 and is gradually straightened up by the curved guide strip 306b 30 so that it enters the delivery channel or runway 165 in an upright position, as indicated in Fig. 5.

Since the pusher 193 and the flap-presser slide 302 are both actuated by the same operating means shown in the patent referred to above, the slide 302 halts in its upper position while the package is being pushed off the pusher 193 to the delivery table, thus avoiding any possible interference with the free passage of the package. Stamp-presser slide 305 with its rollers 304, is 35 also held stationary during this operation, as the top surface 302a of the flap-presser slide 302 supports the stamp-presser slide 305 by contacting with the bottom surface 305a thereof.

As mentioned above, the motions and the timing of the vertical and horizontal pushers 193 and 195, respectively, and the transfer and positioning of stamps are the same as in the machine described in Patent No. 1,058,579, previously referred to, except that the motion of the stamp-presser is produced by the movement of the package.

While the invention has been illustrated in conjunction with the type of machine disclosed in the patent referred to above, it will be understood that it is useful in any type of packaging

machine in which it is desired to apply a stamp or label to the package.

What is claimed is:

1. The combination with means for lifting a package vertically in upright position, the package having a top flap, of a flap-presser for bearing down on said flap while the package is being lifted, mechanism for moving a stamp across the top of said package in overlying relation to said flap-presser, a vertically movable stamp-presser for pressing the stamp down against the top of the package while the latter is being lifted, brushes for wiping the ends of the stamp down over the sides of the package as the latter is being lifted, and stationary guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

2. The combination with means for lifting a package vertically in upright position, the package having a top flap, of a flap-presser for bearing down on said flap while the package is being lifted, mechanism for moving a stamp over the top of said package in overlying relation to said flap-presser, a vertically movable stamp-presser for pressing the stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

3. The combination with means for lifting a package vertically in upright position, the package having a top flap, of a flap-presser for bearing down on said flap while the package is being lifted, a vertically movable stamp-presser for pressing a stamp down against the top of the package while the latter is being lifted, and guides arranged to engage the back of the package as it is being lifted, the upper ends of said guides being inclined with respect to the lower part to tilt the package and thus withdraw the flap-presser from under said stamp and withdraw the top of the package from contact with said stamp-presser, stationary rollers arranged to engage the top of the package at the end of its upward movement, a pusher for ejecting the stamped package sidewise from said means, and a curved guide strip for tilting the package back into upright position as it is being ejected from said means.

4. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, and guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

5. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

6. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

7. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

8. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

9. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

10. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

11. The combination with means for lifting a package vertically in upright position, the package having a top flap, of a vertically reciprocable flap-presser for bearing down on said flap while the package is being lifted, a vertically movable stamp-presser for pressing a stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser.

ers arranged to engage the top of the package at the end of its upward movement, a pusher for ejecting the stamped package sidewise from said means, and a curved guide strip for tilting the package back into upright position as it is being ejected from said means.

5. The combination with means for lifting a package vertically in upright position, the package having a top flap, of a flap-presser for bearing down on said flap while the package is being lifted, mechanism for moving a stamp over the top of said package in overlying relation to said plate, a vertically movable stamp-presser for pressing the stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser, stationary rollers arranged to engage the top of the package at the end of its upward movement, a pusher for ejecting the stamped package sidewise from said means, and a curved guide strip for tilting the package back into upright position as it is being ejected from said means, said means including a vertically reciprocable pusher plate.

6. The combination with means for lifting a package vertically in upright position, the package having a top flap, of a flap-presser for bearing down on said flap while the package is being lifted, mechanism for moving a stamp over the top of said package in overlying relation to said plate, a vertically movable stamp-presser for pressing the stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser, stationary rollers arranged to en-

gage the top of the package at the end of its upward movement, a pusher for ejecting the stamped package sidewise from said means, and a curved guide strip for tilting the package back into upright position as it is being ejected from said means, said flap-presser including a vertically reciprocable slide and a resilient flap-presser plate mounted on said slide.

7. The combination with means for lifting a package vertically in upright position, the package having a top flap, of a flap-presser for bearing down on said flap while the package is being lifted, mechanism for moving a stamp over the top of said package in overlying relation to said plate, a vertically movable stamp-presser for pressing the stamp down against the top of the package while the latter is being lifted, members for wiping the ends of the stamp down over the sides of the package as the latter is being lifted, guides arranged to engage the back of the package as it is being lifted, the upper ends of said guides being inclined with respect to the lower part to tilt the package and thus withdraw the flap-presser from under said stamp and withdraw the top of the package from contact with said stamp-presser, stationary rollers arranged to engage the top of the package at the end of its upward movement, a pusher for ejecting the stamped package sidewise from said means, and a curved guide strip for tilting the package back into upright position as it is being ejected from said means, said stamp-presser including a vertically reciprocable slide and a resilient flap-presser plate mounted on said slide.

8. The combination with means for moving a package having a flap on one face, with said face leading, of a flap presser for bearing against said flap and moving with said package, mechanism for moving a stamp across the said face in overlying relation to said flap presser, means for pressing the stamp against said face and flap presser, and means for producing a relative withdrawing movement in the plane of said face between said flap presser and said package to withdraw the flap presser from under the stamp.

JAMES W. LEARY.
